UNITED STATES PATENT OFFICE.

EDWARD HAGER, OF HENSLEY, WEST VIRGINIA.

CLOTHES BOILER.

Application filed July 1, 1926. Serial No. 119,890.

This invention relates to wash boilers and aims to provide a novel form of wash boiler wherein the clothes boiled therein will not rest on the bottom of the boiler, but at the 5 same time, will be subjected to the action of the boiling water within the boiler.

Another object of the invention is to provide a boiler wherein the clothes being washed will not be submerged in the water, 10 but will be supported above the body of water within the boiler, novel means being provided for directing the boiling water to the clothes, when the water passes through the clothes to clean them.

15 A still further object of the invention is to provide a boiler of this character which may be easily disassembled to clean the elements thereof.

With the foregoing and other objects in 20 view which will appear as the description proceeds, the invention resides in the combination and arrangement of parts and in the details of construction hereinafter described and claimed, it being understood that 25 changes in the precise embodiment of the invention herein disclosed, may be made within the scope of what is claimed, without departing from the spirit of the invention.

Referring to the drawings:

30 Figure 1 is a vertical sectional view through a clothes boiler constructed in accordance with the invention.

Figure 2 is a vertical sectional view taken at right angles to Figure 1.

35 Figure 3 is a plan view of the boiler, the cover being removed.

Figure 4 is a sectional view taken on line 4—4 of Figure 2.

Referring to the drawings in detail, the 40 reference character 5 indicates the body portion of the boiler which in the present showing is rectangular in formation, but it is to be understood that the size and shape of the boiler may be varied without departing 45 from the spirit of the invention.

The reference character 6 indicates the inner water containing receptacle, which is 50 of a height to extend to a point substantially intermediate the ends of the body portion 5, the upper end thereof being beveled as at 7, the beveled surface being provided with openings 8 to permit fluid to pass there-through and into the inner receptacle 6.

55 Mounted within the body portion and resting on the upper edge of the inner receptacle is a clothes container 9 which has its

upper end disposed in proximity to the upper end of the body portion 5 as clearly shown by Figures 1 and 2 of the drawings. Arranged in the wall of the clothes container are openings 10 and 11, the openings 11 being disposed above the openings 10 and as shown are larger than the openings 10 to the end that when the water within the clothes container reaches the openings 11, 60 the water may rush from the clothes container. 65

The bottom of the clothes container is formed with an opening through which the pipe 12 extends, the lower end of the pipe 70 12 being connected with the convexed base 13, which is formed with openings 14, through which the water may pass.

A flange indicated at 15 is formed on the 75 pipe and rests on the bottom of the clothes container, there being provided a collar 16 cooperating with the flange 15 to secure the pipe in an upright position.

As shown by Figure 2, this pipe is of a length to extend to a point above the upper 80 edge of the body portion 5, to the end that water passing through the pipe will pass outwardly at the upper end thereof and fall downwardly onto the clothes contained in the container 9. 85

Openings 17 are formed in the bottom of the clothes container 9 and permit water to pass outwardly through the bottom of the container. Mounted on the upper end of the pipe 12 is a removable deflector 18' 90 which includes a substantially broad member 18 having downwardly extended side portions 19 spaced from the upper end of the pipe 12 to direct water downwardly. 95

The cover of the boiler is indicated at 20 100 and is hingedly connected to the body portion by means of the hinges 21, the central portion of the cover being provided with a pipe 22 to allow steam to pass from the boiler.

A drain opening is provided in the inner receptacle and is normally closed by means of the plug 23, to the end that water in the boiler may be drawn off when the same becomes dirty, and replaced with clean 105 water.

Embedded in the bottom of the body portion is an electric heating element 24 which may be of any desired construction, whereby the same may be connected with a suitable 110 source of electricity supply for heating the contents of the inner receptacle.

Handles 25 form a part of the clothes container and afford means whereby the clothes container may be readily and easily removed.

- 5 From the foregoing it will be obvious that the inner receptacle may be filled with water and the clothes placed in the clothes container, whereupon the heating element is put into operation causing the water to boil in 10 the inner receptacle.

As the water boils in the inner receptacle, it will pass upwardly through the pipe 12 where it will impinge upon the inner surface of the deflector 18 and be directed 15 laterally and downwardly onto the clothes in the clothes container, to the end that the boiling water will pass through the clothes and drain back into the inner receptacle.

I claim:

- 20 In a clothes boiler, a body portion, an inner receptacle within the body portion and having its upper edge beveled inwardly

and having openings formed in the upper edge thereof, the walls of the openings being inclined towards the interior of the 25 inner receptacle, a clothes container in said body portion and superposed on said inner receptacle having openings in the side wall thereof and having openings in the bottom thereof, a pipe extending through the bottom 30 of the clothes container, means for removably securing the pipe to the clothes containing receptacle, a hollow base having openings to permit water to pass upwardly 35 into the pipe, an adjustable removable deflector mounted on the upper end of the pipe and having downwardly extended side portions to direct fluid downwardly, and the upper edges of said clothes containing receptacle extending inwardly providing 40 handles.

In testimony that I claim the foregoing as my own, I have hereto affixed my signature.

EDWARD HAGER.
